UNITED STATES PATENT OFFICE.

LAUREN S. BEARDSLEY, OF NAUGATUCK, CONNECTICUT.

DESIGN FOR AN INSULATOR-HOLDER.

SPECIFICATION forming part of Design No. 24,189, dated April 9, 1895.

Application filed March 4, 1895. Serial No. 540,527. Term of patent 7 years.

To all whom it may concern:

Be it known that I, LAUREN S. BEARDSLEY, a citizen of the United States, residing at Naugatuck, in the county of New Haven and State of Connecticut, have invented a new and original Design for Insulator-Holders, of which the following is a specification.

The design consists of an insulator holder the upper portion of which is provided with a spirally-formed projection, the lower portion also having a spirally-formed part, and being provided in its upper portion, below the spirally-formed projection, with an opening, ribs being formed on the sides of the holder, as shown.

In the accompanying drawing, which represents a vertical elevation of the holder embodying my design, A represents the body-portion of the same, and B is the opening, C representing the ribs.

What I claim, and desire to secure by Letters Patent, is—

The design for an insulator-holder as shown and described.

Dated this 27th day of February, 1895.

LAUREN S. BEARDSLEY.
